(57) **CLAIM**

The ornamental design for a charging bracket as shown and described.

DESCRIPTION

FIG. 1 is a front perspective view of a charging bracket showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of the charging bracket showing the rear element in a first alternative position; and, FIG. 10 is a rear perspective view of the charging bracket showing the rear element in a second alternative position. The broken lines depicting the remainder of the charging bracket and the mobile device nesting in the charging bracket form no part of the claimed design.
